COMBINED TRAY AND RECEPTACLE
HOLDER

Neal W. Liebel, Erie, Pa.

Application August 26, 1948, Serial No. 148,312

Term of patent 3½ years
(Cl. D44—10)

To all whom it may concern:

Be it known that I, Neal W. Liebel, a citizen of the U. S. A., residing at Erie, in the county of Erie and State of Pennsylvania, have invented a new, original, and ornamental Design for a Combined Tray and Receptacle Holder, of which the following is a specification, reference being had to the accompanying drawing, forming part thereof.

In the drawing

Fig. 1 is a front elevational view of a combined tray and receptacle holder, showing my new design;

Fig. 2 is a plan view; and Fig. 3 is a side elevational view thereof.

I claim:

The ornamental design for a combined tray and receptacle holder, as shown.

NEAL W. LIEBEL.
